UNITED STATES PATENT OFFICE.

JACOB H. BLAETZ, OF PHILADELPHIA, PENNSYLVANIA, ASSIGNOR TO
ROBERT PILLING AND RICHARD MADELEY, OF SAME PLACE, TRAD-
ING AS THE FIRM OF PILLING & MADELEY.

DESIGN FOR A STOCKING.

SPECIFICATION forming part of Design No. 34,700, dated June 25, 1901.

Application filed May 1, 1901. Serial No. 58,398. Term of patent 7 years.

To all whom it may concern:

Be it known that I, JACOB H. BLAETZ, a citizen of the United States, residing in Philadelphia, Pennsylvania, have invented and 5 produced a certain new and original Design for a Stocking, of which the following is a specification.

My design for a stocking is fully shown in the accompanying drawing, which represents 10 a side view of the stocking.

The design comprises, essentially, the leg, having alternate closely-knitted and open-work vertical stripes, an ankle with narrower open-work stripes in its rear portion, and a 15 foot with solid heel, sole, and toe.

In the drawing, 1 represents the closely-knitted stripes of the leg and ankle, 2 the wide open-work stripes of the leg, and 3 the narrower open-work stripes of the rear portion of the ankle, 4 representing the solid heel, 5 the solid sole, and 6 the solid toe, of 20 the stocking.

In the stocking illustrated the close and open-work stripes in the front of the leg are carried down along the front of the ankle, 25 the instep, and the top portion of the foot; but the essential features of the design are as above stated.

Having thus described my invention, I claim and desire to secure by Letters Patent—

The design for a stocking, substantially as described and as shown in the accompanying drawing.

In testimony whereof I have signed my name to this specification in the presence of 35 two subscribing witnesses.

JACOB H. BLAETZ.
